HORN DEVICE

Norman F. Lewis, Wilkinsburg, Pa., assignor to
The Westinghouse Air Brake Company, Wil-
merding, Pa., a corporation of Pennsylvania

Application October 31, 1940, Serial No. 363,724

8 Claims. (Cl. 116—142)

This invention relates to horn devices and more particularly to the type embodying flexible diaphragm means adapted to be vibrated at a rapid rate by variations in fluid pressure to produce sound.

The principal object of the invention is the provision of an improved horn device embodying a novel diaphragm means or unit which, as compared to prior devices of this type, is more flexible, is operative by fluid under pressure over a greater range of pressures, has longer life, and does not require as fine adjustments or as great exactness in the manufacture of the different parts of the device in order to operate as desired.

Other objects and advantages will be apparent from the following more detailed description of the invention.

In the accompanying drawing; Fig. 1 is a fragmentary sectional view of a horn device embodying the invention; Fig. 2 is an enlarged sectional view of a portion of the horn device shown in Fig. 1; and Fig. 3 is a plan view of one of the diaphragm elements of the improved horn device.

Description

As shown in the drawing, the horn device comprises a body 1 and a horn bell 2 which may be formed integral with said body and which projects from one end thereof. A flexible diaphragm unit 3 is disposed in the body 1 and at one face of said diaphragm unit the body is provided with an annular cavity 4. The horn bell 2 has a passage 5 open to the cavity 4 through an annular seat rib 6 which is formed integral with the body 1 and extends into the cavity 4.

The body 1 has an annular shoulder 7 disposed in coaxial relation to the seat rib 6 and in a plane spaced slightly from said seat rib. This shoulder is of slightly less diameter than the outside diameter of the diaphragm unit 3 and is provided for engagement by said unit around its edge adjacent the cavity 4.

At the opposite face of the diaphragm unit the body 1 has an annular cavity in which there is disposed a nut 8 having screw-threaded engagement with the body for movement relative thereto toward or away from said diaphragm unit. This nut has projecting from its inner face an annular shoulder 10 arranged in coaxial relation with shoulder 7 in the body and adapted to engage the outer face of the diaphragm unit 3 opposite that engaged by the shoulder 7. The diameter of the shoulder 10 is less than that of the shoulder 7 so as to engage the diaphragm unit in an annular region spaced radially inwardly from the shoulder 7, whereby upon screwing the nut 8 into the body 1 the diaphragm unit may be deflected or flexed in the direction of the seat rib 6. Between the nut 8 and diaphragm unit 3 is a cham-

ber 11 which is in constant communication with the atmosphere through a breather port 12.

In cavity 4 there is disposed a laminated valve 14 adapted to cooperate with the annular seat rib 6 for controlling communication between said cavity and the passage 5 in the horn bell 2, said valve being secured to the diaphragm unit as will be later described. The degree of flexing of the diaphragm unit 3 and the pressure with which the valve 14 is normally urged against the seat rib 6 is adapted to be adjusted to a desired degree by rotation of the nut 8 in the horn body 1 as will be apparent.

The cavity 4 is connected through a choke or restricted port 15 formed in the body 1 to a pipe 16 which is secured to the body. Through this pipe and choke fluid under pressure is adapted to be supplied to the cavity 4 from any suitable source and under the control of any suitable valve means controlled manually or in any other desired manner, for effecting operation of the horn device.

The diaphragm unit 3 which embodies the present invention and provides for attainment of the objects hereinbefore enumerated will now be described in detail.

The preferred form of diaphragm unit 3 shown in the drawing comprises a plurality of disks such as indicated by reference numerals 20, 21 and 22, which are preferably struck from sheet metal and rigidly clamped together around their outer edges between the shoulders 7 and 10 as above described.

The disks 20 and 21 are provided centrally with apertures 23 and 24 respectively, which are preferably of the same diameter, while the disk 22 which is disposed adjacent the valve 14 is provided centrally with an aperture 25 of smaller diameter.

A bolt 26 having a head 27 disposed in the chamber 11 has a main body portion 28 which extends through and has substantially a sliding fit in the aperture 25 in diaphragm 22. The bolt head 27 and body portion 28 are joined by a cylindrical portion 29 of intermediate diameter which extends through the apertures 23 and 24 in the diaphragm disks 20 and 21. The diameter of this cylindrical portion 29 is preferably less than that of the apertures 23 and 24 so as not to contact the diaphragms 20 and 21.

The body portion 28 and cylindrical portion 29 of the bolt 26 are joined by an annular shoulder 30 which tapers outwardly slightly in the direction of the bolt head 27. This taper is provided so that the diaphragm 22 will engage the bolt only at or adjacent to the corner or edge of the aperture 25, thus providing a substantial line contact only between the diaphragm 22 and the bolt 26.

A follower 31 is mounted on the body portion

28 of the bolt at the opposite side of the diaphragm 22, and has a face 32 which is tapered oppositely to shoulder 30 so as to provide a substantial line contact with the diaphragm 22 at or in a region immediately adjacent to the edge of aperture 25 opposite the line of contact with the annular shoulder 30.

The valve 14 comprises a plurality of circular disks 33 which are provided centrally with aligned bores through which the body portion 28 of bolt 26 extends. One end of this pile of disks 33 is mounted against the face of follower 31 opposite that engaging the diaphragm 22, while engaging the opposite face of this pile of disks is a nut 34 having screw-threaded engagement with the end of the bolt, this nut being tightened up against the disks for securely clamping same against the follower 31 and for thereby clamping the diaphragm 22 between face 32 of said follower and the annular shoulder 30 on the bolt.

With the diaphragm 22 thus rigidly secured to the bolt the space between said diaphragm and the inner face 35 of the head 28 on the bolt is slightly greater than the combined thicknesses of the diaphragms 20 and 21 so that with the parts of the diaphragm unit in their normal positions, as shown in Fig. 2, there will be slight clearance space between the face 35 and the adjacent face of the diaphragm 20, it being understood that under this condition the several diaphragms are all urged into contact with each other and against the diaphragm 22 due to the pressure exerted by nut 8 against the diaphragm 20.

The diaphragm 22 is solid except for the central aperture 25, and since it is clamped around its periphery to the body 1 and around the opposite ends of aperture 25 between the shoulder 30 on bolt 26 and face 32 on follower 31 it provides a seal against leakage of fluid under pressure from cavity 4 to chamber 11. This diaphragm is also relatively thin in order to provide long life without rupturing under repeated flexing.

The diaphragm 21 is preferably made in a single piece from relatively thick sheet material and is provided with a plurality of slots 36 which are spaced from each other and extend radially through the diaphragm from the central aperture 24 to a point terminating short of the annular region clamped between the shoulders 7 and 10. These slots separate the central portion of the diaphragm into a plurality of flexible spring-like sections 37 which are adapted to flex independently of each other upon vibration of the central portion of the diaphragm unit. These spring-like sections 37 also prevent the development of excessive internal forces in the diaphragm upon deflection thereof, such as are obtained in solid diaphragms, so that said diaphragm will be more flexible and thereby sensitive to variations in force which control the operation of the horn device to produce sound, as will be later described.

The diaphragm 20 may be like the diaphragm 21 or as shown in the drawing, like the diaphragm 22.

With the parts of the horn device assembled in their working relation shown in the drawing and as above described, the several diaphragms are placed under stress and thereby deflected in the direction of the horn bell 2 by the desired adjustment of the nut 8. With no fluid pressure in cavity 4 the valve 14 is thus forced by the diaphragms into contact with the seat rib 6.

Under this condition the diaphragm 20 is out of contact with the bolt head 28 as shown in Fig. 2. The force of the diaphragms 20 and 21, due to being flexed, is however applied to the diaphragm 22 which transmits same in addition to its own force to the follower 31 for seating the valve 14, as just mentioned.

Operation

If it is desired to cause the horn device to operate to effect a signal, fluid under pressure is supplied to pipe 16 by any suitable means, and from said pipe flows through choke 15 at a restricted rate into cavity 4 at one side of the diaphragm unit 3, the opposite side of which is always at atmospheric pressure through breather port 12. When the pressure of fluid in cavity 4 is thus increased to a degree sufficient to overcome the flexing force now acting on the diaphragm unit, said pressure starts flexing said unit in the direction away from the valve seat 6. This flexing initially occurs in the diaphragm 22 in the region between the bolt 26 and the outer clamped peripheral edge of the diaphragm and will therefore cause deflection of the central portion of the diaphragms 21 and 20 relative to said bolt. This deflection is opposed as will be apparent by the initial stress in the diaphragms 22 and 20 and by the pressure of the spring sections 37 of diaphragm 11.

After a certain slight degree of flexing of the central portions of diaphragms 20 and 21, the diaphragm 20 contacts the inner face 35 of the bolt head 27 so that the pressure of fluid in cavity 35 applied through the diaphragm 22 to the diaphragms 21 and 20 then becomes effective directly on the bolt 26 along with that applied to said bolt by diaphragm 22.

When the pressure in cavity 4 and thereby the force applied through the several diaphragms to the bolt 26 is then further increased to a sufficient degree, said diaphragm unit is operated to pull the valve 14 away from the seat rib 6. A vent communication from cavity 4 past valve 14 to passage 5 in the horn bell is thereby opened which has a flow capacity so in excess of the capacity of choke 15 to supply fluid under pressure to cavity 4, that a sudden reduction in pressure in cavity 4 occurs into the horn passage 5. This reduction in pressure on the diaphragm unit permits the forces in the several diaphragms, due to being flexed, to promptly return said diaphragm unit to its normal position for closing the valve 14. The pressure in cavity 5 then again increases through choke 15 and causes the diaphragm unit 3 to move through another cycle of vibration. This vibration of the diaphragm unit will continue as long as the supply of fluid under pressure to pipe 16 is maintained and will be at such a rate as to create vibrations of the air column in passage 5 within the horn bell which will cause the horn to emit an audible sound suitable for signal purposes.

From the above description it will now be apparent that in the normal position of the diaphragm unit shown in Fig. 2, the diaphragms 20 and 21 and particularly the diaphragm 21 acts merely like a resilient spring to oppose deflection of the relatively thin diaphragm 22 by fluid pressure supplied to cavity 4 whereby the diaphragm unit will promptly respond to a certain pressure in said cavity and start moving. After the unit is thus under motion the diaphragm 20 contacts the bolt head 26 whereby the pres-

sure applied to the diaphragms plus their inertia then becomes effective to promptly unseat the valve 14.

The valve 14 may become slightly unseated by diaphragm 22 before the diaphragm 20 engages the bolt head 27, but the degree of this unseating must not be so great that the resultant loss of fluid pressure from said cavity past said valve will prevent the pressure therein from building up through choke 15 to the degree required for causing the diaphragm unit to operate the bolt 26 to fully unseat the valve 14. It will thus be apparent that the clearance space provided between the bolt head 27 and diaphragm 20, when in their normal positions shown in Fig. 2, must not exceed a certain limit. Within this limit however this clearance space is not critical as long as sufficient is provided to get the several diaphragms under motion before the diaphragm 20 contacts the bolt head 27.

It will be noted that the diaphragm 22 is the only diaphragm which is rigidly secured to the bolt 26 and upon vibration of the diaphragm unit flexes about its substantial lines of contact with shoulder 30 on bolt 26 and face 32 on follower 31. This connection between the diaphragm 22 and bolt 26 is provided to prevent loss of fluid under pressure from cavity 4 to chamber 11 as hereinbefore mentioned. Moreover, this diaphragm is relatively thin, and therefore adapted to withstand repeated flexing about its connection with bolt 26 for an indefinite period of time without rupturing.

In the operation of the device the relatively thick diaphragm 21 resiliently opposes and governs the initial deflection of diaphragm 22, and after the diaphragm 20 engages the bolt head 27 the diaphragms 21 and 20 support the diaphragms 22 against being ruptured by the high operating pressure which may be obtained in cavity 4.

In the normal position of the diaphragm unit shown in Fig. 2, and throughout a portion of the travel of the central portion thereof, the diaphragms 20 and 21 are substantially free of the bolt 26. The slots 36 in the relatively thick diaphragm 31 prevent the development of disruptive internal forces therein upon deflection of the diaphragm, while the independent sections 37 of the diaphragm act in the capacity of springs to control vibration of the unit as well as to support the thinner diaphragm 22 against rupture as hereinbefore mentioned.

While it is difficult to observe the action of the parts while in operation, the above description of operation of the different parts of the improved diaphragm unit is believed to be correct. Regardless of this however it has been found that a diaphragm unit constructed as shown in the drawing and as above described accomplishes all of the objects hereinbefore enumerated, and that horn devices equipped therewith have been surprisingly successful in service. More specifically, this improved diaphragm unit provides the required strength to prevent rupture thereof by the high pressures which may be supplied to cavity 4, and it has been found that, due it is believed to the greater flexibility of the unit, its useful life is indefinite and it will operate as desired over a wide range of operating pressures, such as from seventy to one hundred and forty pounds per square inch. It has also been found that great accuracy in the manufacture of the various parts of the horn device is not required

and neither is it necessary that the nut 8 be adjusted with any great degree of accuracy.

The benefits to be derived from this improved diaphragm unit may be realized in horn devices already in use merely by the substitution of the improved unit for the unit previously employed and this substitution or replacement of units may be effected without returning the device to the factory since any semi-skilled workman with a minimum of instruction will be capable of effecting same.

While only one illustrative embodiment of the invention has been shown and described in detail, it is not the intention to limit the scope to that embodiment or otherwise than by the terms of the appended claims.

Having now described my invention, what I claim as new and desire to secure by Letters Patent, is:

- 20 1. A horn device comprising a body, a flexible diaphragm unit in said body adapted to vibrate in response to variations in fluid pressure for producing sound, said unit comprising a flexible diaphragm clamped around its peripheral edge and adapted to prevent leakage of fluid under pressure from one side to the opposite side thereof and other flexible diaphragm means also clamped around its peripheral edge and having a plurality of spring like sections projecting from the clamped portion thereof and bearing against the first named diaphragm for controlling vibration of said unit and for supporting the first named diaphragm against rupture by the pressure of said fluid, and connecting means associated with said unit operative to provide a rigid connection between the central portions of said diaphragm and diaphragm means after a certain deflection of the unit by fluid pressure, the said diaphragm means being free of said connecting means prior to said certain deflection.
- 25 2. A horn device comprising a body, a vibratory laminated diaphragm unit disposed in said body and clamped thereto around its peripheral edge, and a valve in said body, said diaphragm unit comprising one diaphragm having an operating connection with said valve for vibrating said valve with said unit and another diaphragm which is normally independent of said valve, said diaphragm unit being normally deflected under stress in one direction for operating said valve to provide a differential of fluid pressures on opposite sides of said unit and being deflectable in the opposite direction by said differential of fluid pressure for operating said valve to destroy said differential, the second named diaphragm opposing movement of the unit in said opposite direction, and means arranged to connect said second named diaphragm with said valve after a certain initial movement of the diaphragm unit in said opposite direction.
- 30 3. A horn device comprising a body, a valve in said body, a vibratory laminated diaphragm unit disposed in said body and clamped thereto around its peripheral edge, said diaphragm unit being normally deflected under stress in one direction for operating said valve to provide a differential of fluid pressures on opposite faces of said unit and being deflectable in the opposite direction by said differential of fluid pressures for operating said valve to destroy said differential, said diaphragm unit comprising two flexible diaphragms, a bolt connecting said valve to one of said diaphragms for vibrating said valve with said one diaphragm, said bolt having a shoulder arranged for engagement by the second named
- 35
- 40
- 45
- 50
- 55
- 60
- 65
- 70
- 75

diaphragm after a certain initial deflection of said first named diaphragm in said opposite direction, said shoulder being disengaged from said second named diaphragm when said valve is in the position provided for obtaining said differential of fluid pressures.

4. A horn device comprising a body, a vibratory laminated diaphragm unit disposed in said body and clamped thereto around its peripheral edge, a valve in said body connected to said unit and adapted to vibrate therewith to alternately provide a differential of fluid pressures on opposite sides of said unit and to then destroy said differential for thereby causing vibration of said unit and valve, the connection between said unit and valve comprising a member securing said valve to one diaphragm of said unit for movement therewith, said unit comprising another diaphragm cooperative with the first named diaphragm to oppose movement of said unit by said differential of fluid pressures, the second named diaphragm being free of said member when said differential of fluid pressures is destroyed, and means arranged to connect said second named diaphragm and member after a certain initial movement of said unit under the influence of said differential of fluid pressures.

5. A horn device comprising a body, a vibratory laminated diaphragm unit disposed in said body and clamped thereto around its peripheral edge, a valve in said body connected to said unit and adapted to vibrate therewith to alternately provide a differential of fluid pressures on opposite sides of said unit and to then destroy said differential for thereby causing vibration of said unit and valve, the connection between said unit and valve comprising a bolt secured to said valve and extending through central aligned openings in the diaphragms of said unit, means rigidly clamping said bolt to one of said diaphragms at the opposite ends of the opening therethrough, another of said diaphragms being free of said bolt when said differential of fluid pressures is destroyed, and means associated with said bolt adapted to be engaged by said other diaphragm after a certain initial movement of said unit under the influence of said differential of fluid pressures.

6. A horn device comprising a body, a vibratory laminated diaphragm unit disposed in said body and clamped thereto around its peripheral edge, a valve in said body connected to said unit and adapted to vibrate therewith to alternately provide a differential of fluid pressures on opposite sides of said unit and to then destroy said differential for thereby causing vibration of said unit and valve, the connection between said unit and valve comprising a bolt secured to said valve and extending through central aligned openings in the diaphragms of said unit, means rigidly clamping said bolt to one of said diaphragms at the opposite ends of the opening therethrough, another of said diaphragms being free of said bolt when said differential of fluid pressures is destroyed, and means associated with said bolt adapted to be engaged by said other diaphragm after a certain initial movement of said unit under the influence of said differential of fluid pressures, the second named diaphragm being provided with a plurality of slots spaced from each other and extending radially from the central opening in the diaphragm to near the clamped portion of the diaphragm thereby providing a plurality of resilient members which are independent of each other

and operative to oppose deflection of the first named diaphragm by said differential of fluid pressure and to support said first named diaphragm against said differential of fluid pressures upon connection with said bolt after said initial deflection.

7. A horn device comprising a body, a laminated vibratory diaphragm unit disposed in said body and clamped thereto around its peripheral edge, 10 a valve in said body connected to said unit and adapted to vibrate therewith to alternately provide a differential of fluid pressures on opposite sides of said unit and to then destroy said differential of fluid pressures for thereby causing vibration 15 of said unit and valve, said diaphragm unit comprising two relatively thin outside diaphragms and a central diaphragm of greater thickness, all of said diaphragms having axially aligned openings, the central diaphragm being provided 20 with a plurality of slots spaced from each other and extending radially from the central opening therein to near the clamped portion of the diaphragm, a bolt extending through the aligned openings in the several diaphragms and rigidly 25 connected to said valve, means cooperative with said bolt rigidly clamping one of the outer diaphragms to said bolt at the opposite sides of the axial opening therethrough, the two other diaphragms being free of said bolt when the differential of fluid pressures on said unit is destroyed 30 by said valve, and means on said bolt arranged to be engaged by the other outer diaphragm after a certain initial movement of said unit under the influence of said differential of fluid pressures.

8. A horn device comprising a body, a laminated vibratory diaphragm unit disposed in said body and clamped thereto around its peripheral edge, a valve in said body connected to said unit and adapted to vibrate therewith to alternately provide a differential of fluid pressures on opposite sides of said unit and to then destroy said differential of fluid pressures for thereby causing vibration of said unit and valve, said diaphragm unit comprising at least three flexible diaphragms 40 provided with axially aligned openings, a bolt extending through said openings and having a shoulder adapted to engage the inner face of one of the outer diaphragms and having a head spaced from said shoulder and adapted to engage the outer face of the other outer diaphragm, the distance between said shoulder and head exceeding the combined thicknesses of the diaphragms arranged therebetween, a member carried by said bolt arranged to engage the outer face of the diaphragm engaged on its inner face by said shoulder, means rigidly securing said member against the said one outer diaphragm and connecting said valve for movement therewith, said shoulder and the surface on said member engaging the opposite faces of said one outer diaphragm being tapered in an outwardly direction away from the diaphragm to thereby provide contact with the diaphragm only adjacent the opposite edges of the central opening therethrough, the said distance 50 between said shoulder and head providing for engagement between said head and said other outer diaphragm after a certain initial deflection of said unit under the influence of said differential of fluid pressures for supporting said first named outer diaphragm, the said distance also rendering the said other outer diaphragm and the central diaphragm independent of said bolt at other times.
